PARING AND CORING TOOL

Myron J. Zimmer, Chicago, Ill., assignor to The
Edward Katzinger Company, Chicago, Ill., a
corporation of Illinois

Application March 3, 1938, Serial No. 193,773

1 Claim. (Cl. 30—278)

This invention relates to a paring and coring tool and is designed to provide an auxiliary or additional bearing surface in conjunction with the blade thereof for coaction with the finger of the user when operating the tool, and constructed to overcome any tendency of the fore or index finger of the user to slip or become fatigued during such use.

With the above and other objects in view, as will be apparent, this invention consists in the construction, combination and arrangement of parts, all as hereinafter more fully described, claimed and illustrated in the accompanying drawing, wherein:

15 Fig. 1 is a side elevational view of a paring and coring tool embodying the features of this invention.

Fig. 2 is a bottom plan view of the same.

20 Fig. 3 is a vertical section taken on line 3—3 of Fig. 1.

In the use of devices such as paring and coring tools and the like, the fore or index finger of the user bears upon the trailing or rear edge of the blade adjoining the handle and in the course of continued use the relatively abrupt edge of the blade tends to pinch and irritate the finger of the user. The present invention has in view the provision of a relatively wide guard or bearing in conjunction with the rear edge of the blade adjoining the handle so that a relatively large curved bearing surface is created for the fore or index finger of the user in operating the knife.

Reference being had more particularly to the drawing, 10 designates a blade having transversely convergent sides 11 and 12 to the inner end of which is connected a handle 13. The inner end of the blade is provided with integral wings or collar-forming members 14 adapted to encircle a cap or ferrule 15, mounted on the adjacent end of the handle 13. Attachment of the wings 14 and the ferrule 15, in rigid assembly with the handle 13 may be established through any suitable means, such as tacks or screws 16.

45 The line of convergence of the sides 11 and 12 of the blade extends forwardly from the ferrule end of the handle 13 in substantial longitudinal alignment with the side of the handle as shown in Fig. 1. Adjoining the line of convergence, the

50 side 11 of the blade is struck outwardly to form a longitudinal cutting segment 17 which may be

used as a paring or peeling blade. The outer extremity of the blade is tapered and pointed as at 18 and provided with a sharpened edge 19 for use as a coring or scooping device.

5 Adjoining the handle 13, the edge of the side 11 of the blade (which is in trailing relation to the cutting segment 17 on the side 12 of the blade) is provided with an upstanding ear 20. The body of the ear 20 is preferably dished or curved inwardly from its forward edge to its handleward edge to provide a bearing surface substantially conforming to the contour of the finger of the user. It will also be observed that the blade side 11 and ear 20 (as shown in Fig. 3) provides angularly related outer surfaces or bearings corresponding to the angle of normal flexure defined by the inner surface of the last and next to the last joint of an operator's forefinger when flexed into gripping position thereon.

10 If desired, the surface of the handle adjoining the inner or ferrule end thereof may be provided with ridges 21 of any suitable shape to present added means for preventing slippage of the hand thereon in either direction.

15 From the foregoing it will be apparent that the present invention provides a coring and paring tool having as an integral part thereof a bearing for coaction with the finger of the user which will relieve irritation and fatigue of the fore or index finger of the user, and at the same time affords a device of this character which is capable of inexpensive, expedient production and assembly in mass quantities.

20 What is claimed is:

25 The combination with a blade having transversely convergent sides and a handle at one end thereof, a cutting segment struck from one of said sides in proximity to the line of convergence thereof, an upstanding ear projecting from the upper edge of the blade side normally in trailing relation to said cutting segment, said blade side and said ear, when the operator's forefinger is flexed into gripping position therearound with the junction of the last and next to the last joints 30 of the forefinger against the junction of said blade side and ear, forming angularly related bearing surfaces corresponding to the angle of normal flexure of said joints of the finger.

MYRON J. ZIMMER.
